[57] ABSTRACT

Structure is provided for a dental handpiece comprising an operating instrumentality driven to perform dental operations within the oral cavity. The handpiece is of the air rotor type and hose means delivering air and water to the operating instrumentality is comprised of a flaccid material for an unsupported portion of its length between the handpiece and an adjustable supporting element through which the major portion of the air-water hosing extends. The adjustable supporting element enables placement of the handpiece proximate a working location while supporting the major portion of the hosing length. The flaccid hose portion in combination with the adjustable supporting element enables manipulation of the handpiece with elimination of much of the torque and drag normally encountered. By a second aspect of the invention, a weight is adjustably mounted within the handpiece to enable achievement of a balanced feel to suit the individual choice of an operator, as well as precise manipulation and control.

DENTAL APPARATUS WITH ENHANCED HANDPIECE MANIPULABILITY

BACKGROUND OF THE INVENTION

1. Field of the Invention

The present invention relates to dental apparatus and more particularly to the structure and arrangement of an assembly for a dental handpiece including an operating instrumentality which is powered by an air rotor in the performance of dental operations within an oral cavity. More specifically, the invention contemplates an arrangement whereby the handpiece may be manipulated with enhanced comfort and control.

2. Discussion of the Prior Art

The performance of dental operations, such as the drilling of dental caries, requires considerable delicacy in the manipulation and control of the mechanisms which are utilized. Normally, such mechanisms include a dental handpiece having a slender, somewhat elongated configuration and an operating instrumentality, such as a drill or the like, operably mounted at one end thereof. Power means such as belt driven pulley systems have been utilized to extend to the handpiece in supplying power to drive the drill during dental operations. Since the area within the oral cavity where work must be performed is generally quite sensitive and involves close spacing, great care and accuracy on the part of a dental operator is required.

However, accurate control and manipulation of the handpiece is quite often adversely affected by forces imparted thereto through the mechanisms which are provided to power the operating instrumentality. For example, in prior art dental devices in which the operating instrumentality or drill is driven by a belt and pulley arrangement, significant drag is imparted to the handpiece by the sheer weight of the pulley system which must be moved. Such imparted drag increases the difficulty encountered by the operator in attempting to delicately and carefully control the movement of the handpiece.

Clearly, therefore, it would be advantageous to structure such a dental handpiece system in a manner whereby imparted forces detracting from precise control and manipulation of the handpiece could be eliminated or minimized. Also, the feel or balance of a handpiece involves a significant factor since a good deal of discomfort may be experienced depending upon individualized requirements of particular operators. As in any manipulable tool or device, the ability to individualize the feel or balance of a device will afford significant advantage in providing operator comfort as well as to enhance delicacy of control. Clearly, achievement of individualized balance and comfort in a handpiece would be rendered of little benefit if forces imparted to the handpiece by the driving mechanism were to destroy the balanced feel created.

In prior art devices, easing of the forces imparted to a handpiece has been attempted by introduction of new or improved flexible pulley systems for driving the operating instrumentality of the handpiece, but nevertheless certain deficiencies inherent in this type of apparatus have endured. Bulkiness, inefficiency and a lack of aestheticism are concomitant features of almost all mechanical pulley systems.

The advent of the air rotor handpiece in dental apparatus brought about utilization of hosing for deliver-

ing air and water to power and cool the operating instrumentality or drill of the handpiece. In this type of device, air is applied to drive the rotor of the operating instrumentality, and water is applied to cool the teeth during the dental operation. This type apparatus requires separate hosing for the air and the water, and it has been found that the weight and rigidity of the hosing will produce significant resistive force during manipulative operation of the handpiece. In air rotor type equipment, the weight of the hosing which is utilized introduces drag upon the handpiece and the rigidity of the material introduces torque, thereby reducing mobility and control and obviating much of any advantage which could be derived from a well designed, comfortably balanced handpiece.

In presently known prior art approaches, one expedient which has been utilized is to arrange the equipment, particularly the floor console which houses most of the operative elements of the apparatus, as close as possible to the patient in an attempt to minimize the length of free unsupported hosing. This may be effective to a limited extent but it will introduce other disadvantages, such as encroachment of the equipment console upon the working space of the operator, or encumbrance of the patient.

Accordingly, it will be apparent that equipment which enables minimization or elimination of drag and torque forces created by the weight and rigidity of fluid transmitting hosing in air rotor types of dental equipment, without requiring encroachment upon the working space of an operator or encumbrance of the patient, will involve significant advantages for several reasons, including provision of the opportunity to advantageously utilize a handpiece of superior design and balance.

SUMMARY OF THE INVENTION

Briefly, the present invention may be described as dental apparatus comprising a handpiece including an operating instrumentality manipulable for location relative to an oral cavity, a source of fluid supply, hose means extending between said fluid source and said handpiece for transmitting fluid to effect operation of said operating instrumentality, said hose means comprising a flaccid portion adjacent said handpiece rendering said hose means substantially ineffectual to impart resistive torque to said handpiece during manipulation thereof, and adjustable support means for said hose means enabling selective supported positioning thereof relative to said oral cavity, said support means being operably unconnected with said handpiece and terminating support of said hose means at a distance therefrom to leave unsupported said flaccid hose means portion between said support means and said handpiece.

By a more specific aspect of the present invention, the adjustable support means is provided in the form of self supporting multi-positional support arm such as, for example, a gooseneck.

By an additional aspect of the invention, a weight mounted upon the handpiece may be adjustably positioned relative thereto to effect a desired balanced feel of said handpiece when held by an operator. Adjusting means provided to enable relative positioning between the weight and the handpiece may comprise gear

means operable to drive the weight along the length of the handpiece to a desired position, or a releasable screw mechanism may alternatively be provided whereby the weight may be manually moved to a desired location and held there by tightening of said screw mechanism.

BRIEF DESCRIPTION OF THE DRAWINGS

A better understanding of the present invention may be had by reference to the following detailed description of preferred embodiments thereof taken in connection with the accompanying drawings wherein:

FIG. 1 is a side elevational view of dental apparatus embodying the present invention and showing a dental chair and an appurtenant console with related equipment;

FIG. 1A is a side elevational view of a console similar to that shown in FIG. 1 showing an alternative for the adjustable support means of the invention;

FIG. 1B is a side elevational view showing a dental chair similar to that shown in FIG. 1 wherein the equipment console is mounted upon the back of the chair;

FIG. 1C is a sectional view taken along the line 1C—1C in FIG. 1;

FIG. 2 is a fragmentary longitudinal view depicting a typical dental handpiece in accordance with the present invention;

FIG. 3 is a fragmentary longitudinal sectional view of the handpiece of FIG. 2;

FIG. 4 is a cross sectional view taken along the line 4—4 of FIG. 3;

FIG. 5 is a cross sectional view taken along the line 5—5 of FIG. 3;

FIG. 6 is a fragmentary longitudinal sectional view depicting a second embodiment of a handpiece made in accordance with the present invention;

FIG. 7 is a cross sectional view taken along the line 7—7 of FIG. 6;

FIG. 8 is a cross sectional view taken along the line 8—8 of FIG. 6;

FIG. 9 is a fragmentary longitudinal view depicting an alternative embodiment of the handpiece of the invention;

FIG. 9A is a fragmentary sectional view of the handpiece of FIG. 9;

FIG. 10 is a cross sectional view taken along the line 10—10 of FIG. 9A;

FIG. 11 is a fragmentary sectional view of a dental handpiece showing another alternative embodiment of the invention; and

FIG. 12 is a cross sectional view taken along the line 12—12 of FIG. 11.

DETAILED DESCRIPTION OF THE PREFERRED EMBODIMENTS

Referring now in detail to the drawings, there is shown in FIG. 1 dental apparatus embodying the elements of the present invention and including a dentist's chair 10 having located in proximity thereto a console member 12 comprising a table portion 13, with the combined structure having mounted therein equipment normally useful in the performance of ordinary dental operations. Thus, the table portion 13 will contain thereupon much of the ordinary apparatus which is utilized to provide a more commodious environment

for the patient, while at the same time being internally structured to house and support other equipment such as the mechanical, electrical, hydraulic or pneumatic elements required in powering and operating the apparatus. Since the present invention is particularly adaptable for utilization in connection with air rotor types of dental equipment, it is intended that the console 12 contain sources of air and water which are applied, in a manner to be further discussed hereinafter, in the operation of the dental equipment involved. The particular structure and arrangement of the console, as well as the nature and configuration of the power equipment including the sources of air and water, are not shown in detail and may be configured in accordance with conventional prior art arrangements. The present invention is considered adaptable and usable with a variety of such types of equipment and a detailed description of this portion of the operative structure is not considered necessary to a full understanding of the nature and operation of the invention.

The basic elements of the present invention are embodied in adjustable support means comprised of a flexible jointed metal pipe or gooseneck 16, a dental handpiece 18, and a flaccid hose portion 20 extending between the gooseneck 16 and the handpiece 18. These elements cooperate, in a manner to be more fully described, to provide the benefits of the invention. A clip mount 22, which is not an essential feature of the invention, may be provided at the end of the gooseneck 16 in order to provide a repository for the handpiece 18 when not in use. Although gooseneck 16 is presently preferred other types of self supporting multi-positional supporting arms may be employed within this invention. Further, if desired the multi-positional supporting arm may be arranged to be retractable into table 13 (or unit 34 of FIG. 1b) without departing from this invention.

The handpiece 18, shown in somewhat greater detail in FIG. 2, comprises a rotor 24 which is located at the operating end thereof and which includes the usual operating instrumentality such as a bur 26 or other similar device adapted to perform dental operations within an oral cavity. The operating instrumentality 26 is powered through the rotor 24 by means of air directed through the flaccid hose portion 20 which is configured as two separate flaccid circular hoses 20a and 20b, with one of the hoses supplying air to drive the rotor 24 and with the other of said hoses supplying water for cooling the operating instrumentality 26 during operation of the device. The structure and operation of the rotor end 24 of the handpiece 18 may be conventional and in accordance with known principles.

It should be understood that the portion of flaccid hose means 20 is operably interconnected in flow relationship with additional hose portions which extend through the gooseneck 16 to the console 12, and through the handpiece 18 to the rotor 24. As will be discussed more fully hereinafter, these additional hose portions are preferably not of the same flaccid material as the portion 20.

It will be apparent that use of the handpiece 18 involves delicate, sensitive operations requiring precise manipulation and control, and any factor which detracts from or limits the manipulability of the hand-

piece 18 will produce significant detriment in the functioning of the apparatus. In prior art devices of the air rotor type, the hosing necessary to provide air and water has been such as to cause drag and torque upon the handpiece during operation. Usually, the length of the hose which must extend between the source of air and water, i.e., the console 12, and the handpiece 18 involves a weight which creates drag upon the handpiece 18 thereby reducing comfort and maneuverability when the dentist is working within the oral cavity and when he is required to move to different positions in and around the dental chair. Shortening the length of hose to overcome this detriment would require that the console 12 be brought uncomfortably close to the chair and the patient, thereby encumbering the patient and limiting the availability of work space around the chair. In order to enable sufficient mobility without requiring undue proximity between the chair and the console, it would be necessary to extend or lengthen the unsupported amount of hose which would extend between the console and the handpiece. Such a hose length will, merely by virtue of its weight alone, cause significant drag upon the handpiece thereby adding to the difficulty encountered by the dentist in adequately controlling and manipulating the handpiece.

Additionally, the materials used in forming prior art hosing are of sufficient rigidity that the operator is caused to experience torque forces when twisting or rotating the handpiece during use.

The present invention is aimed toward alleviating these drag and torque forces. Basically, the invention accomplishes this by provision of flexible adjustable support means for the major portion of the length of the hose means which transmits the air and the water from the console 12 to the handpiece 18. As shown in the drawing, this flexible adjustable support means comprises a gooseneck 16. However, it will be apparent that variations from the specific structure shown may be provided. Basically, the concept requires that the major portion of the weight of the hose be supported in a manner which enables free and easy adjustability and location thereof in conformance with the requirements for locating the handpiece 18. Thus, with the major portion of the hose supported in this manner, no drag will be caused upon the handpiece as a result of the weight of the hosing utilized.

Such adjustable support means cooperate with a suitable length of flaccid hose means 20 which extends between the end of the adjustable support means 16 and the handpiece 18. The length of the flaccid hose means 20 is of such a light and flexible nature that it creates minimal drag and torque effects upon the handpiece 18. The material chosen for the length of hose means 20 is of such a nature that little or no resistance is developed to movement of the handpiece 18 and, accordingly, free and easy manipulation and location thereof during the performance of dental operations is enabled. The particular material and configuration of the hose means 20 will be described in greater detail hereinafter, but it should be apparent that in the performance of work within the oral cavity, the dentist may first locate and adjust the gooseneck 16 to a location generally within proximity of the point at which work is to be performed. This can be done with ease and facility, and as a result the major portion of the

hose length will be appropriately located and completely supported by the gooseneck 16. With the gooseneck 16 appropriately located, the dentist may then easily manipulate the handpiece 18 in the vicinity of the oral cavity since, due to the nature and composition of the flaccid hose means portion 20, a sufficient degree of movement appropriate to the performance of ordinary dental operations is accommodated.

The FIGS. 1A and 1B show alternative arrangements 10 for the dental apparatus shown in FIG. 1. In FIG. 1A there is shown a console 12a having an articulated adjustable support member 28 extending therefrom in place of the gooseneck 16 of FIG. 1. A shortened section of a gooseneck 16a extends between the articulated support 28 and the flaccid hose means 20a. A dental handpiece 18a is connected to the flaccid hose means 20a in identically the same manner as is shown in FIG. 1 with the only difference between the structures of the FIGS. 1 and 1A being that the gooseneck member 16 is somewhat shortened with portions 15 thereof being replaced by the articulated member 28.

The articulated support member 28 comprises a plurality of rod members 30 joined by a group of pivotal joints 32 with the entire articulated assembly being expandable and adjustable to locate the handpiece 18a proximate a working location. Of course, the gooseneck 16a will operate in generally the same manner as the articulated support 28 to provide adjustable supported positioning of the handpiece 18a. With the articulated support member 28 and the gooseneck 16a in place, the portions of hose means extending therethrough will be firmly supported in a desired position avoiding the occurrence of drag on the handpiece 18a. Of course, the flaccid hose means 20a will operate in the same manner as described in connection with FIG. 1 to provide similar results eliminating torque.

FIG. 1B shows a second alternative embodiment 40 wherein the source of air and water is affixed to the rear of the dental chair 10. As shown, a unit 34 is attached at the rear of the chair 10 and has extending therefrom a gooseneck 16b containing therein appropriate hose elements to transmit air and water to the operating instrumentality of a handpiece 18b connected to the gooseneck 16b by flaccid hose means 20b in much the same manner as previously described. It will be apparent that by mounting the power source 34 upon the back of the chair 10, closer proximity of the handpiece 18b to the patient may be achieved without unduly encumbering the work space around the chair. However, the present invention may nevertheless be advantageously utilized in providing the hose means 45 partially within the gooseneck 16b and partially unsupported, a flaccid hose portion 20b, thereby to significantly contribute to reduction of the torque and drag upon the handpiece 18b.

As previously pointed out, the length of hose means 50 which is contained within the gooseneck 16 may be of any ordinary configuration, or it may be identical to the flaccid hose means 20 which is provided exteriorly of the gooseneck 16. Since the gooseneck 16 will fully support and maintain the length of the hose means contained therein in any desired position, no drag or weight effects upon the handpiece will be produced by 55 this portion of hose means. FIG. 1C is an enlarged ver-

sion of a portion of FIG. 1 showing the manner whereby the hose means may be mounted and supported within the gooseneck 16. In the preferred embodiment of the present invention described herein, the hose means which extend within the gooseneck 16 are not comprised of the flaccid material utilized in the formation of the hose means 20, but instead are configured to comprise a pair of ordinary hoses 40a and 40b formed of conventional material which operate to transmit air and water to the hose means 20.

The specific material utilized in the formation of the hose means 20 of the preferred embodiment described herein is a silicone rubber compound which exhibits the desired characteristics giving rise to the benefits of the present invention. Such silicone rubber compounds are commercially available and may be obtained from the Dow Corning Corporation under the trademark Silastic.

Table I below sets forth data enabling a comparison between standard hoses presently in use and the silicone hoses of the present invention.

TABLE I

	Unsupported Hose Length (in)	Density (gm/in)	ID × OD (in)	Torque* (gm-cm)	Hose
Standard Hose No. 1	66	1.0	.125×.250	50	
Standard Hose No. 2	66	0.68	.125×.187	45	
Silicone Hose No. 1	18	0.17	.062×.095	2 to 5	
Silicone Hose No. 2	18	0.26	.078×.125	2 to 5	
Silicone Hose No. 3	18	0.34	.062×.125	5 to 8	

*Maximum reaction torque with hose internal pressure at 0 psi while in normal extended position.

As will be seen from the above cited data, the hose torque produced upon the handpiece is significantly reduced by utilization of hose means 20 of the present invention, represented by the three different samples identified as Silicone Hose Numbers 1, 2 and 3. It will be seen that, where hose arrangements previously known, i.e., Standard Hoses Numbers 1 and 2, will produce a torque on the hand piece of 45 or 50 gram-centimeters, the present invention enables reduction of this torque or drag to levels of between 2 and 8 gram-centimeters as indicated above. It should be understood that these readings were taken with the equipment in the normal operating position, but with no air or water flow through the hoses and with the internal hose pressure at 0 psi. However, it will be seen that little or no difference in the torque transmitted to the handpiece 18 will be realized with the hose means 20 under the normal operating pressure of about 32 psi since almost all of the torque or drag which is developed in hindering free manipulability of the handpiece 18 results from the stiffness and weight of the hose material and not from the operating pressures of the elements of the apparatus involved.

It has been found that the present invention enables the resistive forces produced upon a dental handpiece to be limited to no more than 18 gram-centimeters.

Accordingly, it will be seen that with the arrangement of the present invention the handpiece 18 will be free of significant encumbering drag and torque forces

thereby enabling greatly enhanced manipulability and heightened comfort and control during the performance of dental operations.

With the handpiece 18 alleviated of reactive torque and drag in the manner described, means may be effectively provided whereby the balance and feel of the handpiece may be varied and adjusted to suit the preference of different operators as well as to enable the instrument to be more readily, precisely and comfortably handled. By a second aspect of the present invention, a weight is provided within the handpiece, together with means for adjusting the position of the weight relative to the handpiece, thereby to enable achievement of an individualized balanced feel. Such individualized adjustability is possible with heightened sensitivity in the feel of the handpiece due to the fact that the torque and drag forces, which would otherwise counteract the balancing force of such a weight, have been reduced or eliminated in the manner previously described.

A first embodiment of the present invention which provides an adjustable weight device in the handpiece 18 is depicted in FIGS. 2-5. A weight member 50 is mounted within a housing 52 which also includes therein a worm 54 engaging the weight 50 along an internal worm gear threaded opening 56 for driving the weight 50 longitudinally along the interior of the handpiece 18. A pair of end members 58 and 60 provide rotatable support for the worm 54 within the housing 52, with the member 60 also providing support together with a member 60a for a pair of gear shafts 62 and 64. Shafts 62 and 64 which rotatably mount a pair of spur gears 66 and 68 which are in engagement with the toothed interior of a control member 70 that has graduations marked on the exterior thereof. Control member 70 is rotatably mounted upon the exterior of the handpiece 18 to enable controlled rotation of the spur gears 66 and 68. The worm 54 has affixed at one end thereof of a driven spur gear 72 which is engaged by the spur gears 66 and 68 for rotation thereby to drive the worm 54 and thus effect positioning of the weight 50 along the length of the handpiece 18 by virtue of the engagement of the worm gear 54 with the threaded internal opening 56 in the weight 50. Thus, by manipulating the member 70 positioned at the end of the handpiece 8, the weight 50 may be adjusted to provide a balanced feel for the handpiece which will be suited to the particular desire of an individual user. The weight 50 is provided with a pair of longitudinally extending circular openings 74 and 76 through which the hose means 21a and 21b extend, respectively, to enable sliding motion of the weight 50 along the length of the handpiece 18.

The hose means 21a and 21b which extend internally of the handpiece 18 are preferably formed of metallic material and not from the flaccid material utilized for the hose means 20a and 20b, although they may be flaccid. As shown in FIG. 3, the hose means 20a and 20b are fitted, respectively, over the ends of hose means 21a and 21b and are held there by a pressed fit or by any other appropriate means, such as the couplings 77 and 79. Since the hose means 21a and 21b are internally formed to be part of, and movable directly with, the handpiece 18, it will be apparent that

no need arises to form this portion of the structure from flexible material. On the other hand, formation of the hose means 21a and 21b from rigid or metallic material enables the weight means 50 to slide longitudinally therealong without rotating relative to the housing 52 and with little friction. Thus, when the worm 54 is rotated it will operate to move the weight 50 longitudinally along the hoses 21a and 21b which will act as a tracking mechanism for the weight 50 and obstruct rotation thereof.

The right end of the housing 52 has formed thereupon threads 61 which enables placement of an end cap 63 having internal threads engaging the threads 61 for mounting. An end sleeve 65 engages the end of the housing 52 and serves to retain the hose means 21a and 21b. The member 70 is marked with graduated indicia on the outside thereof to indicate the relative position of the weight 50.

A second embodiment whereby weight means may be adjustably manipulated to alter the balanced feel of the handpiece is depicted in FIGS. 6, 7 and 8. A cylindrically shaped weight member 80 has its outer surface formed with spiral threads which engage the inner threaded surface 82 of a cylindrical sleeve 84 mounted within a housing 86 of a handpiece 18c. A ball bearing 88 rotatably supports the sleeve 84 which is driven to rotate within the housing 86 by manipulation of a graduated control member 90 engaging a pair of spur gears 92 and 94 which mesh with an end 96 of the sleeve 84 thereby enabling the sleeve 84 to be rotated by manipulation of the member 90. As the sleeve 84 is rotatably driven, its engagement with the weight 80 will operate to position the weight 80 longitudinally within the housing 86 along the length of the handpiece 18c in much the same manner as was previously described in connection with the weight 50. The hose means 20a and 20b may be supported in a manner similar to that described in connection with FIGS. 2-5 and similar internal hose means 21a and 21b will operate as a tracking mechanism for the weight 80 which is provided with a pair of cylindrical openings 97 and 98 formed internally thereof through which the hose means extend. An end sleeve 65 is also provided in a manner similar to that previously described to retain the hose means 21a and 21b. An end support member 67 is provided to rotatably support the shafts 69 and 71 of the spur gears 92 and 94, and as the member 90 is rotated it will rotate the sleeve 84 thereby causing the weight 80 to track along the hoses 21a and 21b to be longitudinally located at any desired position along the handpiece 18c.

A third alternative embodiment for mounting a weight within a dental handpiece is shown in FIGS. 9, 9A and 10. In this arrangement a simplified manual approach for adjustably moving the weight means is disclosed. A handpiece 18d includes an upper removable cover member 99 which permits access to the head of a screw member 104 adapted to threadably engage a weight member 100. The handpiece 18d includes a housing member 102 having a horizontal upper portion 103 which defines a longitudinal slot 106 extending therealong. By loosening the screw 104 the weight 100 may be moved longitudinally along the handpiece 18d with the screw 104 sliding along the longitudinal slot 106 as the weight member 100 is brought to a desired

position. At this point, the screw 104 may be tightened to firmly engage the housing portion 103 between the upper surface 107 of the weight 100 and the underside of the head of the screw 104. After appropriate adjustment of the location of the weight 100, the cover member 99 may be replaced and the handpiece 18d will be ready for utilization in the usual manner with the location of the weight 100 providing the individualized balanced feel desired by the operator.

An additional alternative embodiment to the weight mounting arrangements previously described is shown in FIGS. 11 and 12. A weight 110 is slidably mounted within a housing 118 of a handpiece 18e, a portion only thereof being shown in FIG. 11. A removable cover member 112 overlies a horizontal upper portion 119 of the housing 118 and permits access to a stud member 114 having a spring 116 in cooperative relationship therewith and maintained in compression between the underside or portion 119 and a foot element 115 of the stud 114. The stud 114 comprises a head member 117 which preferably has a serrated underside 124. The portion 119 defines a longitudinally extending slot 120 through which the stud 114 extends, with a serrated surface 122 preferably being provided on the upper side of the portion 119 located on either side of the slot 120 in a manner to engage the underside of the head 117. By lifting the head 117 and the stud 114, the spring member 116 may be compressed to allow sliding longitudinal movement of the weight 110 along the length of the handpiece 18e. When the head 117 is released the spring 116 will apply a force against the foot 115 to effect engagement of the undersurface 124 of head 117 with the serrated surface 122 of the portion 119. Accordingly, the weight 110 will be firmly held in the desired location by the interengagement of the serrated surfaces 122 and 124 which is maintained in a firm manner by the operation of the spring 116. The metallic hose means 21a and 21b will extend through the weight 110 and be supported thereby in a manner similar to that previously described and will operate as a tracking mechanism for the weight 110.

From the foregoing it will be apparent that the handpiece 18 shown in FIG. 1, as well as any of the handpieces shown and described herein, may be appropriately configured to comprise weight means adjustment as described herein. With the handpiece alleviated of drag and torque from the hoses which are normally provided in the transmission of air and water, the balanced feel of a handpiece may be adjusted with much greater sensitivity to suit the individualized requirements of the operator. Accordingly, it will be seen that by the combined operation of an arrangement including the gooseneck 16 and the flaccid hose means 20, with the adjustable balancing weight means included within the handpiece, there will be afforded a dental apparatus of greatly superior manipulability with significantly enhanced comfort and precision of control.

Although the present invention has been defined in connection with specific structural embodiments thereof, it is to be understood that many variations and modifications of the structure shown and described may be effected by those skilled in the art without departure from the spirit and scope of the invention.

What is claimed is:

1. Dental apparatus comprising a handpiece including an operating instrumentality manipulable for location relative to an oral cavity, a source of fluid supply, hose means extending between said fluid source and said handpiece for transmitting fluid to effect operation of said operating instrumentality, said hose means comprising a flaccid portion adjacent said handpiece rendering said hose means substantially ineffectual to impart reactive torque to said handpiece during manipulation thereof, and adjustable support means for said hose means enabling selective supported positioning thereof relative to said oral cavity, said support means being operably unconnected with said handpiece and terminating support of said hose means a distance therefrom to leave unsupported said flaccid hose means portion between said support means and said handpiece.

2. Dental apparatus according to claim 1 wherein the overall reactive force upon said handpiece resulting from the weight and stiffness of said hose means is less than 18 gram-centimeters.

3. Dental apparatus according to claim 1 wherein said flaccid hose means portion is formed of silicone rubber tubing.

4. Dental apparatus according to claim 1 wherein said adjustable support means comprises flexible jointed metal tubing.

5. Dental apparatus according to claim 1 wherein said adjustable support means comprises a plurality of articulated metal tubes, and pivotable interconnecting means pivotally joining said metal tubes together at their ends.

6. Dental apparatus according to claim 1 comprising a weight movably mounted on said handpiece, and means for moving said weight relative to said handpiece for effecting a desired balance of said handpiece when held by an operator, relative to

7. Dental apparatus according to claim 6 wherein said handpiece comprises a generally elongated configuration, and wherein said moving means comprise gear means engaging said weight and being manipulable to drive said weight along the length of said handpiece to any one of a plurality of positions.

8. Dental apparatus according to claim 7 wherein said gear means comprise a worm extending longitudinally of said handpiece, gear thread means formed upon said weight and operably engaging said worm, means to obstruct relative rotation between said handpiece and said weight, and a control member manipulable to rotate said worm for effecting movement of said weight along said handpiece.

9. Dental apparatus according to claim 7 wherein said gear means comprise a sleeve member rotatably mounted upon said handpiece and having gear threads formed internally thereof, said weight comprising gear threads formed thereupon operably engaging said sleeve internal gear threads, means for obstructing relative rotation between said weight and said handpiece, and a control member manipulable to rotate said sleeve member thereby to drive said weight relative to said handpiece to a desired position.

10. Dental apparatus according to claim 6, wherein said moving means include a screw threadedly mounted in said weight for movement between a tightened and a loosened condition, said handpiece having a longitudi-

dinal passage therein through which said weight is movable and having a longitudinal slot communicating with said passage, said screw extending through said slot and being operatively engageable with a portion of the handpiece adjacent said slot when in said tightened condition to clampingly hold said weight in a preselected position, said screw and weight being movable in said slot and passage, respectively, when said screw is in said loosened condition.

10 11. Dental apparatus according to claim 6 wherein said moving means comprise spring means interposed between said weight and said handpiece, said handpiece and said spring means having a pair of frictionally engageable confronting surfaces, said spring means being held between said weight and said handpiece to generate a spring force holding said confronting surfaces together, and being manipulable to release said spring force for enabling movement of said weight relative to said handpiece to a selected position with reengagement of said confronting surfaces by application of said spring force holding said weight in said selected position.

12. Dental apparatus according to claim 11 wherein said confronting surfaces are serrated.

13. Dental apparatus according to claim 7 comprising portions of said hose means extending interiorly of said handpiece and being formed of rigid material and being in fluid conducting relationship with said flaccid hose means portion, said weight having passage means through which said rigid hose means extends for slidably mounting said weight thereon for longitudinal movement, said rigid hose means preventing relative rotation between said weight and said handpiece.

35 14. A dental handpiece comprising an elongated handle, motor means carried by said handle for driving an operating instrumentality, a weight connected to said handle and movable longitudinally thereof for altering the balance thereof, and means for releasably holding said weight in a preselected position.

40 15. A dental handpiece according to claim 14 further comprising means for moving said weight longitudinally of said handle.

45 16. A dental handpiece according to claim 15 wherein said moving means comprises gear means engaging said weight means for driving said weight along the length of said handle to any one of a plurality of different selected positions.

50 17. A dental handpiece according to claim 16 wherein said handle has a longitudinal passage therein and said gear means comprises a worm extending longitudinally of said handle in said passage, gear thread means formed upon said weight, said weight being disposed within said passage with said gear thread means operably engaging said worm, means to obstruct relative rotation between said handle and said weight, and means for rotating said worm for effecting longitudinal movement of said weight along said handle.

55 18. A dental handpiece according to claim 16 wherein said weight moving means comprises a sleeve member rotatably mounted upon said handle and having gear threads formed internally thereof, said weight comprising gear threads formed thereupon operably engaging said sleeve internal gear threads, means for obstructing relative rotation between said weight and

said handle, and means for rotating said sleeve member thereby to drive said weight relative to said handle to a desired position.

19. A dental handpiece according to claim 14 wherein said holding means comprises screw means extending relative to said handpiece and threadedly engaging said weight for adjustment between a tightened and a loosened position, said handle being formed to permit movement of said weight relative thereto when said screw means are in said loosened position, said handle also being operatively engageable frictionally between said screw means and said weight means for holding said weight in a selected position relative to said handle.

20. A dental handpiece according to claim 14 wherein said holding means comprise spring means interposed between said weight and said handle, said handle having a pair of frictionally engageable confronting surfaces, said spring means being positioned between said weight and said handle for producing a spring force for holding said surfaces in frictional engagement and manipulable to release said spring force, whereby to enable movement of said weight relative to said handle to a selected position.

21. A dental handpiece according to claim 20, wherein said confronting surfaces are serrated.
